UNITED STATES PATENT OFFICE

155,790

DESIGN FOR A SMOKING PIPE HOLDER

Herman Epstein, Kansas City, Mo.

Application June 14, 1948, Serial No. 146,950

Term of patent 7 years

(Cl. D85—8)

To all whom it may concern:

Be it known that I, Herman Epstein, a citizen of the United States, residing at Kansas City, in the county of Jackson and State of Missouri, have invented a new, original, and ornamental Design for a Smoking Pipe Holder, of which the following is a specification, reference being had to the accompanying drawing, forming a part thereof.

Fig. 2 is a plan view thereof; and

Fig. 3 is a left-hand end view of Fig. 1.

The dominant features of my design reside in those portions shown in full lines.

I claim:

The ornamental design for a smoking pipe holder, as shown and described.

HERMAN EPSTEIN.
